UNITED STATES PATENT OFFICE.

FRITZ GEGAU, OF STECKBORN, SWITZERLAND.

SKEINING DEVICE.

Application filed October 23, 1926, Serial No. 143,629, and in Switzerland November 2, 1925.

The subject matter of the present invention is a device for skeining hanks of yarn on reels, i. e. for subdividing the hanks by interlacing a skeining thread between the leas. In order to simplify the device in comparison to known mechanical skeining devices the device according to the present invention is provided with receiving means arranged within and without the reel and cooperating with holders for the skeining thread, said holders being alternately delivered from the inner receiving means to the outer receiving means and vice versa by a relative movement of said receiving means.

Constructional examples of the subject matter of the present invention are illustrated on the accompanying drawings, in which:

Fig. 1 is an elevation view of the device;
Fig. 2 is a vertical section along line II—II in Fig. 1;

Figs. 3 and 4 show in an elevation view and in a front view respectively means for securing the reel against rotation;

Figs. 5 and 6 show details in elevation;

Fig. 7 shows in a plan-view an implement for subdividing the hanks;

Figs. 8-17 are diagrammatic sketches serving to explain the operation;

Fig. 18 shows in an elevation with parts shown in section a modified constructional example;

Fig. 19 is a section along line IXX—IXX in Fig. 18 with parts shown in an end view, and

Figs. 20-23 show details.

Referring now to the first constructional example illustrated in Figs. 1-7 the reel 1 is turnably mounted in pedestal bearings 2 and 3 which are open at the top and fixed on a table 4. The latter rests on rollers 5 turnably mounted in extensions 6 of a table 7 forming part of the frame of the device and being supported on standards 8. The table 4 together with the reel 1 is thus displaceable in the axial direction of the latter on the rollers 5. A plurality of hanks 9 are arranged on the reel and the skeining thread is obtained from bobbins 10 mounted above the reel. Means are provided to secure the reel 1 against rotation and to fix it in different angular positions. These

means are illustrated in Figs. 3 and 4 and comprise a disk 11 fixed on the axle 12 of the reel and provided with a number of holes 13 corresponding to the angular positions in which the reel has to be secured. With the holes 13 a pin 14 cooperates, mounted in an arm 15 which is fixed to a gudgeon 16 rigidly held in the pedestal 2. A spring 17 urges the pin 14 to engage one of the holes 13 and a lever 18 cooperates with the pin 14 to withdraw the latter and to compress thereby the spring 17 when it is intended to turn the reel 1 and secure it in a different angular position. 19 denotes an organ extending in the axial direction of the reel 1 and provided with prongs 20 adapted to enter into the hanks and to subdivide the latter into a number of leas 9' which have to be tied together by the skeining thread. The organ 19 is carried by arms 21 pivoted at 22 so that it can be swung into the position illustrated in Fig. 7 in which the prongs 20 penetrate through the hanks 9.

With each hank 9 a needle 23 cooperates which is provided at its top with a plate spring 24 (Fig. 6) for clamping the skeining thread to the needle. The needles 23 are held in needle clamps of a similar type as that used in hand operated embroidering machines. Every needle clamp consists of a base part 25 and a clamping member 26 pivoted on the base part at 27; a plate spring 28 presses the clamping member 26 on the needle 23 (Fig. 6). The needle clamps are fixed on a bar 29 by means of a set screw 30 and are adjustable along said bar 29. The latter is fixed to two supports 31 slidably arranged on horizontal spindles 32 mounted in pedestals 33. A reciprocating movement is imparted to said supports 31 and thereby to the needles by means of a cam-disk 34 mounted on the main driving shaft 35. A groove 36 is provided in one of the end faces of the disk 34 and a roller 37 cooperates with said groove. The roller 37 is turnably mounted in one end of a two armed lever 38, the upper end of which is connected by a link 39 to one of the supports 31. The lever 38 is fixed on a shaft 40 turnably mounted in brackets 41 fixed to the underside of plate 7. The other support 31 (Fig.

1) is coupled to an arm 42 fixed to the shaft 40.

In order to open the needle clamps a horizontal rod 43 passes above all the clamping members 26 and is carried by two vertical arms 44, which are supported by cranks 46 and links 45 between the arms and pedestals 33. The arms 44 are pulled in the downward direction by means of a cam disk 47 fixed to the shaft 35 with which a roller 48 at the end of a crank arm 49 cooperates. The latter is fixed on a rock shaft 50 to which the cranks 46 for the two arms 44 are attached. Upon the rotation of the shaft 35 the cam-disk 47 and the roller 48 cause a downward movement of the arms 44, whereby the clamping members 26 are depressed and the needles 23 released.

Besides the needle clamps receiving the needles 23 and arranged outside of the reel 1 there are means provided inside the reel 1 for that purpose which means comprise a horizontal straight edge or bar 51 provided with a number of apertures 52 corresponding to the number of needle clamps and in which the needles are frictionally held by a plate spring 53 (Fig. 6). The bar 51 is slidably mounted in three supports 54, rollers 55 being provided for that purpose, so that the bar 51 may be withdrawn from the reel 1 when the latter has to be turned. The supports 54 are slidably arranged on axles 56 and 56' mounted in pedestals 57. A reciprocating motion of the supports 54 in the axial direction of the axles 56 is caused by the disk 58, having a lateral groove 59 with which a roller 60 cooperates. The latter is mounted in the lower end of a two armed lever 61 fixed on a shaft 62 mounted in brackets 62' and the upper end of the lever 61 is connected by means of a link 63 to the middle support 54 (Fig. 1). The outer supports 54 are connected to the arms 64 on the shaft 62 by similar links 63. A collar 65 limits the endwise extreme position of the bar 51 so that the apertures 52 are exactly opposite the needle clamps when the bar 51 is manually pushed into the reel.

The means for displacing the reel 1 in the axial direction comprise a pinion 66 fixed to the main driving shaft 35 and cooperating with a gear wheel 67 mounted on a counter-shaft 68. On the latter a drum 69 is fixed provided with a cam groove 70 on its circumference with which a roller 71 cooperates. The roller 71 is turnably mounted in the lower end of a two-armed lever 72 pivoted at 74 in a bracket 73, the upper end of this lever 72 is connected by means of a link 75 to a bracket 76 fixed to the lower side of the table 4 on which the reel 1 is mounted. A turning of the drum 69 causes a reciprocating movement of the table 4 and thereby of the reel in the axial direction of the latter. 77 denotes the driving pulley.

The operation of the above described device will now be explained with reference to the diagrammatic Figs. 8-17.

The reel 1 is placed from above into its bearings of the pedestals 2 and 3 and fixed in the desired position by causing the pin 14 to enter one of the holes 13. Thereupon the bar 51 for receiving the needles 23 is pushed into the reel 1 by hand and the member 19 is swung towards the reel so that its prongs 20 penetrate through the hanks 9 and subdivide the latter into leas 9'; the prongs thus forming openings necessary for the passage of the needles.

Then the needles 23 held by the needle clamps outside of the reel 1 are threaded with the skeining thread from the bobbins 10 and the driving shaft 35 is caused to rotate. By the action of the cam disk 34 and the parts operated therefrom the needle clamps are moved towards the reel 1 and simultaneously the bar 51 is moved towards the needle clamps and receives the needles. The holding members 26 are depressed and the needles are released and drawn through the hanks by the receding bar 51. When the latter has reached its extreme position it moves towards the needle clamps and in the mean time the reel has been displaced in the axial direction by the action of the drum 69 and the parts cooperating therewith, so that the needle held by bar 51 is opposite the next opening as is shown in Fig. 9. The needles are partly pushed through the hank by the bar 51 and are received by the needle clamps, as the latter and the bar 51 move simultaneously towards and away from each other, the cam grooves 36 and 59 being opposed to each other. The holding members 26 are released by the bar 43 whereby the needles 23 are again held by the clamping members and are completely drawn through the hanks by the clamping members moving away from the reel and the latter is further axially displaced so that a needle occupies the position illustrated in Fig. 10. The above mentioned movements of the bar 51, of the needle clamps and of the reel continue and the following positions of one needle relatively to the hank is shown in Figs. 11 and 12. The reel is then axially displaced in the opposite direction to which it moved previously and the needle occupies successively the positions shown in Figs. 13-17. The skeining thread thus interlaces the various leas and its ends are tied to a knot either manually or by means of a knotting device.

When it is desired to skein the hanks also at other parts of the circumference of the reel, the latter is turned into the desired position and the above described operations are continued with the reel in the new position.

The second constructional example illus-

trated in Figs. 18-23 differs from the first constructional example in the arrangement of the bar 51. With the first constructional example the bar 51 had to be withdrawn in 5 the axial direction for permitting a removal or a turning of the reel, whilst in the second constructional example the bar 51 is so arranged that it remains in the reel 1 when the latter is removed. To this end the bar 10 51 is carried by means of axles 78 slidably mounted in brackets 79 fixed to the axle 12 of the reel 1. The axles 78 are provided with angular heads 80 in which the bar 51 is carried by set screws 81, Figs. 22 and 23. 15 In order to permit the axial displacement of the reel 1 relatively to the bar 51 a slot 82 is provided so that the angular head 80 may slide on the bar 51 without being hindered by the set screw 81 when the reel 1 is displaced. 20 Coil springs 83 are connected with their one end to the bar 51 and with their other end to the angular head 80 to provide for a resilient connection between the latter and the bar 51.

25 The bar 51 is of such a length that its ends are loosely inserted in heads 84 of the axles 56 (Fig. 21) which are slidably mounted in the pedestals 57. The reciprocating movement of the axles 56 and thereby of the 30 bar 51 towards and away from the reel 1 is caused by similar means as in the first constructional example, of which the two-armed lever 61, arm 64 and the link 63 are shown in Figs. 18 and 19. The reciprocating movement of the table 4 relatively to the table 7 35 is also caused by means similar to those described above with reference to the first constructional example and of which the upper end of the two-armed lever 72 and the link 75 are shown in Figs. 18 and 19. The clamping devices for the needles and their operative connection to the driving shaft are not illustrated in this constructional example as they are similar to those of the first constructional example.

The skeining device according to the present invention is of a simple design and it ensures a reliable operation and a high output.

I claim:

50 1. A device for skeining hanks, comprising in combination, a reel adapted to hold the hanks, means adapted to impart a reciprocating movement to said reel and in the axial direction of the latter, means adapted 55 to hold the skeining threads, means arranged outside the reel and adapted to receive said thread holding means, means arranged inside the reel and adapted to receive said thread holding means, a main driving 60 shaft, and an operative connection between said main driving shaft and said means for receiving said thread holding means and said means to impart a reciprocating movement to said reel whereby said thread holding means are alternately delivered from said

outer means for receiving said thread holding means to said inner means and vice versa, said reel being displaced by one lea during every such delivery.

2. A device for skeining hanks, comprising in combination, a reel adapted to hold the hanks, means adapted to impart a reciprocating movement to said reel and in the axial direction of the latter, needles adapted to hold the skeining threads, needle clamps 70 arranged outside the reel and adapted to be reciprocated towards and away from said reel, a needle bar arranged inside the reel and adapted to be reciprocated towards and away from said reel, a main driving shaft, 75 and an operative connection between said main driving shaft and said needle clamps and said needle bar and said means for imparting a reciprocating movement to the reel whereby said needles are alternately delivered from said needle clamps to said needle bar and vice versa and pass thereby through the hank, said reel being displaced by one lea during every such delivery.

80 3. A device for skeining hanks, comprising in combination, a reel adapted to hold the hanks, means adapted to impart a reciprocating movement to said reel and in the axial direction of the latter, needles adapted to hold the skeining threads, needle clamps 85 arranged outside the reel and adapted to be reciprocated towards and away from said reel, a needle bar arranged inside the reel and adapted to be reciprocated towards and away from said reel, a main driving shaft, an operative connection 90 between said main driving shaft and said needle clamps and said needle bar and said means for imparting a reciprocating movement to the reel whereby said needles are alternately delivered from said needle clamps to said needle bar and vice versa and pass thereby through the hank, said reel being displaced by one lea during every such delivery, and means for securing said reel in 95 different angular positions.

100 4. A device for skeining hanks, comprising in combination, a frame, a table slidably mounted on said frame, pedestal bearings 105 open at the top on said table, a reel inserted in said pedestal bearings and turnable therein, means to impart a reciprocating movement to said table in the axial direction of said reel, needles adapted to hold the skeining threads, needle clamps arranged outside 110 the reel and adapted to be reciprocated towards and away from said reel, a needle bar arranged inside the reel and supported by pedestals arranged beyond both ends of said reel and adapted to be reciprocated towards and away from said reel and to be endwise displaceable, a main driving shaft, and an operative connection between said main driving shaft and said needle clamps and said needle bar and said means for imparting 115 a reciprocating movement to said reel.

120

125

130

ing a reciprocating movement to the reel whereby said needles are alternately delivered from said needle clamps to said needle bar and vice versa and pass thereby through the hank, said reel being displaced by one lea during every such delivery, said operating connection including disks provided

with cam grooves mounted on said main driving shaft, and rollers and levers cooperating with said disks and with said needle clamps and said needle bar.

In testimony whereof, I have signed my name to this specification.

FRITZ GEGAU.
